UNITED STATES PATENT OFFICE.

CHARLES T. BLOOMER, OF NEWARK, NEW YORK.

PAPER BOX.

1,184,715.

Specification of Letters Patent. Patented May 30, 1916.

Application filed December 9, 1914. Serial No. 876,314.

To all whom it may concern:

Be it known that I, CHARLES T. BLOOMER, a citizen of the United States, residing at Newark, in the county of Wayne and State 5 of New York, have invented a new and useful Paper Box, of which the following is a specification.

The present invention appertains to cartons or paper boxes, such as are employed 10 for holding and carrying eggs and other commodities, the primary object of the invention being the provision of novel and improved means for fastening and sealing the cover of the box closed.

15 This invention contemplates the provision of such fastening or sealing means for the box cover, that when the cover is fastened and sealed in closed position, the cover cannot be reopened by maliciously inclined or 20 unwarranted persons for changing or interfering with the contents of the box, without so injuring or mutilating the fastener and seal, or the box and its cover, as to enable the tampering to be readily detected 25 by the purchaser or recipient of the box.

It is also within the scope of the invention, to provide a cover fastener and seal which will be inexpensive and simple in construction, which may be employed upon 30 various paper boxes or cartons, and which will be simple, efficient and thoroughly practical in use.

With the foregoing and other objects in view which will appear as the description 35 proceeds, the invention resides in the combination and arrangement of parts and in the details of construction hereinafter described and claimed, it being understood that changes in the precise embodiment of 40 the invention herein disclosed can be made within the scope of what is claimed, without departing from the spirit of the invention.

The invention is illustrated in the accompanying drawing, wherein:—

Figure 1 is a perspective view of an egg box or carton embodying the present fastener and seal, and illustrating the cover closed and sealed. Fig. 2 is a reduced plan view 50 of the blank from which the box is formed. Fig. 3 is an enlarged sectional view through the fastener and seal, taken on the line 3—3 of Fig. 4. Fig. 4 is a sectional view on the line 4—4 of Fig. 3, parts being broken 55 away. Fig. 5 is a fragmental front view

of a box embodying a modified form of fastener and seal.

In the drawing, there is illustrated an egg box embodying the body 1'', and the back of which is provided with a swinging 60 cover 2''. The type of box illustrated is to be taken as conventional, since the present improvements may be employed upon various styles of boxes and cartons with equal success and propriety.

In carrying out the invention, the free edge of the cover 2'' is provided with a tuck flap 3'' which is insertible behind the front wall of the body 1'' when the cover 2'' is closed, there being a fold line 4'' between the cover 2'' and its flap 3''.

The tuck flap 3'' is provided with a slot 5'', the ends of which terminate short of and adjacent the fold line 4'', and which forms an approximately semi-circular tab 75 6'' projecting from the free portion of the cover 2'' within the opening formed in the flap 3'' by the slot 5'' and which opening extends adjacent to the fold line 4''. The slot 5'' is so formed, as to provide a relatively small lug or ear 7'' projecting centrally from the free portion of the tab 6'', the lug 7'' being tapered from its basal to its free end.

A circular seal 8'' is imprinted or otherwise provided upon the tab 6'', and the adjacent portion of the cover 2'', so that one half of the seal 8'' is disposed upon the outer side of the tab 6'', while the other half is disposed upon the adjacent portion 90 of the cover 2''.

Glue or other adhesive material may be provided upon the back or inner side of the tab 6'', and glue or other adhesive material may be disposed upon the outer side 95 of the lug 7'', while glue or adhesive material may be provided upon the inner and outer faces or sides of the front wall of the body 1'', immediately below and above a horizontal slot 12'' provided in the front wall of the body. The slot 12'' is of segmental contour, with its straight edge disposed uppermost, and the slot 12'' is so arranged as to enable the lug 7'' to be passed inwardly therethrough when the tab 100 6'' is moved over the outer side or front wall of the body when the cover 2'' is closed.

When the box is employed as an egg container and carrier, a filler or cellular rack 110

13" is preferably disposed within the body 1", for receiving and separating or spacing the eggs.

The upper edge of the front wall of the body is provided with a pair of V-shaped notches or cuts 14" for receiving those portions of the flap 3" between the ends of the slot 5" and the fold line 4".

In order to fasten and seal the cover 2", after the box has been filled, the tuck flap 3" is tucked behind the front wall of the body when the cover 2" is swung to closed position, and the tab 6" moves downwardly over the outer side of the front wall, the glue or mucilage portions of the tab 6" and lug 7" having been previously moistened. The lug 7" is then inserted inwardly through the slot 12", this being facilitated due to the contour of the slot, and when the cover 2" and tab 6" are forced firmly into place, the tab 6" will engage the ends of the slot 12", to provide a snug fit, and the glue will cause the tab and lug to adhere to the front wall of the box, whereby the cover will be firmly held down. Especial attention is directed to the fact that the opening provided in the flap 3", by the slot 5", enables the contents of the box to press outwardly against the lug or ear 7", to cause the said lug to adhere to the front wall of the box below the slot 12". As a result of the introduction of the lug 7" through the slot 12", and the fastening of the lug to the inner side of the front wall of the body, the tab 6" will be locked in place, so that it cannot be pried loose, should the glue between the tab 6" and front wall not dry properly. Furthermore, the contents of the box in resting against the front wall of the body through the opening provided in the flap 3", will cause that portion of the front wall in rear of the tab 6", to move outwardly against the tab, to cause the tab and front wall to adhere properly. In this manner, the layers of the structure will be firmly held together under the pressure of the contents of the box, so that the layers of the box will be held together while the glue sets or hardens.

The seal 8" which is provided upon the tab 6" and the adjacent portion of the cover 2", gives the appearance of an independent seal pasted over the corner between the cover and front wall of the box, but it being noted that half of the seal carried by the tab 6" is integral with the cover so that the attachment of the tab 6" to the front wall, will provide a secure fastening means for the cover, especially in view of the provision of the lug 7" engaged through the slot 12". As a result, the cover will be so sealed in closed position, that it is impossible for competitors or unwarranted persons, to pry or work the cover loose, so that it can be opened and the contents of the box changed

or tampered with. This will enable the producer to transmit fresh eggs and other commodities to the customer, without danger of the contents being removed or tampered with during transit or handling. The tab 6" and its lug 7" being both fastened to the front wall of the box, provide a double lock or seal, the lug 7" enhancing the effectiveness of the seal, since in being disposed within the body, it cannot be tampered with or pried loose, without so injuring or mutilating the box, as to cause a detection thereof. It is also evident that either one of the glued portions will enable the cover to be effectively sealed, should the other glued portion fail to adhere properly.

If desired, only one or two of the glued portions need be employed, and if the glued portion between the tab and body is eliminated, it will be obvious that the purchaser or recipient of the box may readily loosen the cover by running a knife or other suitable implement under the tab 6", and cutting the tab, which will immediately release the cover and enable the box to be opened.

Especial attention is directed to the fact that there are portions of the paper or other stock between the ends of the slot 5" and the fold line 4", will tend to hold the tab 6" in the same plane as the tuck flap 3" and consequently when the tuck flap is inserted into the body of the box behind the front wall thereof, the tab 6" will be held snugly and tightly against the outer side or face of the front wall, so that the glue between the tab and front wall will cause the said portions to adhere properly. Furthermore, should a person attempt to maliciously pry up the tab 6", those portions of the stock between the ends of the slot 5" and the fold line 4" will be torn so as to enable the tampering to be readily detected.

The variation illustrated in Fig. 5, resembles the first form, with the exception that the lug of the tab and the slot of the front wall of the body are eliminated. Thus, the cover 2^a of the body 1^a is provided with the tuck flap 3^a having an arcuate slot 5^a whose end terminates short of the fold line 4^a between the flap 3^a and cover 2^a, so as to provide an approximately semi-circular tab 6^a movable over the outer side of the front wall of the body 1^a, the upper edge of the front wall being provided with the notches or cuts 14^a for receiving those portions of the flaps 3^a between the ends of the slot 5^a and the fold line 4^a. Thus, the tab 6^a will be held snugly against the front wall of the body when the tuck flap is inserted behind the said front wall and whereby the glue may set properly between the tab and body.

Having thus described the invention, what is claimed as new is:—

1. A paper box having a swinging cover

provided with a tuck flap at its free portion
insertible behind one wall of the box when
the cover is closed, the said flap having a
slot terminating short of the cover and pro-
viding a tab foldable over the outer side of
the said wall and tending to remain in the
plane of the flap, said wall having notches
for receiving those portions of the flap be-
tween the ends of the slot and the cover.

10 2. A paper box having a swinging cover
provided with a tuck flap at its free portion
insertible behind one wall of the box when
the cover is closed, the said flap having a
slot terminating short of the cover and pro-

viding a tab having a lug projecting from 15
its free portion, the tab tending to remain
in the plane of the flap, said wall of the box
having a slot through which the lug is in-
sertible and having notches for receiving
those portions of the flap between the ends 20
of the slot and the cover.

In testimony that I claim the foregoing
as my own, I have hereto affixed my signa-
ture in the presence of two witnesses.

CHARLES T. BLOOMER.
